ATTEST

UNITED STATES PATENT OFFICE.

GUSTAV FISCHER, OF BERLIN, GERMANY.

METALLIC MATRIX-PLATE.

No. 837,394.

Specification of Letters Patent.

Patented Dec. 4, 1906.

Application filed February 15, 1905. Serial No. 245,774.

To all whom it may concern:

Be it known that I, GUSTAV FISCHER, manufacturer, a subject of the King of Prussia, German Emperor, residing at No. 16 Fried-
richstrasse, Berlin, German Empire, have invented new and useful Improvements in Metallic Matrix-Plates, of which the following is a specification.

My invention relates to matrices for producing galvanoplastic reproductions or electrotypes of printers' forms, wood blocks, and the like.

According to my invention the operation of forming a matrix by pressing or forcing down the type or block upon a soft-metal plate is essentially facilitated by the back of the plate being provided with grooves, whereby the metal during the pressing operation more readily rises or swells up, so that the lights in the galvanoplastic cameo shell are of such depth that subsequent treatment of the same, such as chiseling or cutting out, is rendered unnecessary.

One form of plate according to my invention is illustrated in the accompanying drawings, in which—

Figure 1 shows a back view of a corner portion of a plate having longitudinal and transverse grooves. Fig. 2 is a section on the line A-B of Fig. 1.

The plate *a* is preferably made of lead, and the back of it by rolling, stamping, cutting, or otherwise is treated in such a manner that grooves, furrows, or the like are formed, which are preferably made so that they decrease in size from the surface of the plate inward.

In the drawings the plate *a* is illustrated as being provided with longitudinal and transverse V-shaped grooves *b*, whereby a large assemblage of pyramidal elevations (in the figures shown as truncated pyramids) result. The back of the plate thus presents a checkered surface. Naturally the grooves, furrows, or the like may run in an inclined direction and simple parallel grooves or furrows—that is, without crossing—may also be provided.

The depth, size, shape, and number of the depressions, and thus of the projections or

elevations resulting therefrom, may greatly vary, depending upon the nature of the original, whether a wood block, form, or the like.

If by means of a press an engraved wood block or the like is pressed down onto a plate prepared in the above-described manner, a very sharp intaglio impression results without the original being in any way injured, for owing to the pliability of the recessed plate the pressure necessary is very much less than in the case of an ordinary soft-metal plate. For example, with my new indented plate fifty atmospheres pressure is sufficient, where ninety atmospheres would be requisite with an ordinary soft-metal plate.

A special advantage of my new method is that on the application of pressure the metal very readily rises or swells up, as it were. Thus the lights in the galvanoplastic cameo shell or electrotype, which is made by means of the mold or matrix, are of such depth that subsequent cutting or chiseling of these portions is rendered wholly unnecessary. Another advantage of my improved metal matrix-plate is that it presents a regular surface on the back, which is a matter of much convenience in backing or mounting the electrotype shell. Not only is the work facilitated, but the character of the matrix finally obtained is very superior.

Having thus described my invention, I claim as new—

1. A metallic matrix-plate for producing galvanoplastic reproductions, the back of which is provided with parallel grooves.

2. A metallic matrix-plate for producing galvanoplastic reproductions, provided on its back with crossing grooves.

3. A metallic matrix-plate for producing galvanoplastic reproductions, provided on its back with longitudinal and transverse V-shaped grooves, substantially as set forth.

In witness whereof I have hereunto signed my name, this 2d day of February, 1906, in the presence of two subscribing witnesses.

GUSTAV FISCHER.
